LOOSE-LEAF DISPLAY CALENDAR

Orion P. Winford, St. Paul, Minn., assignor to
 Brown & Bigelow, St. Paul, Minn., a corpora-
 tion of Minnesota

Application March 26, 1951, Serial No. 217,464

5 Claims. (Cl. 283—2)

1

This invention relates to a loose-leaf calendar or display device where it is desired to hold a series of sheets in a pad or one upon the other so that the sheets may be referred to when desired.

A primary feature of this invention is to provide a very economical means of supporting the sheets in loose-leaf form so that the front sheet with the current calendar can be taken from the front of the pad and placed upon the rear thereof and retained for future reference if desired. In 10 accomplishing this, I have provided a holder for the sheets which may be made from paper and which is integral in construction so that the holder or binder may be made economically.

A further feature resides in providing a hanger binder for the loose-leaf sheets of the calendar which is formed by reinforcing the front of a sheet adapted to form the binder by a cloth backing member, which is applied to the front of the binder sheet so as to strengthen the same and to permit the hanger tongue to be stamped from the reinforced portion of the sheet. It is obvious that cloth or any other reinforcing material may be applied to the sheet adapted to form the binder hanger before the hanger tongue is stamped out of the body of the sheet. Further, by stamping the hanger tongue out of the rectangular sheet which forms the front display sheet of the hanger, no waste material is left when the hanger or binder sheet is formed, thereby economizing in the cost of manufacture of my binder hanger for the loose-leaf sheets.

The binder hanger sheet provides the front display sheet for the upper portion of the calendar above the calendar pad. Ordinarily this sheet supports a picture or illustration supplied for the purpose of making the calendar more attractive. Usually a colored picture or print is attached to the cover sheet, and this means of decoration also provides the means of closing the opening made in the body of the front sheet in stamping out the hanger tongue from the body of the sheet.

The upper edge of the binder hanger may be turned in the same manner as the upper and lower ends of present calendars are made. The turning of the upper edge of the cover sheet provides a reinforcing or strengthening means adjacent the hanger tongue, which is folded back of the front sheet and projects upwardly to supply the means of holding the hanger when it is hung upon the wall. The turned upper edge of the binder hanger sheet also holds this edge straight to give a neat, finished appearance to the same.

The loose-leaf sheets of the calendar may be in any form, and each of the sheets are formed with a horizontal slot through which the tongue of the binder hanger extends to hold the sheets collected together, thereby forming the several sheets making up the calendar and display.

2

The various features and details of the invention will be clearly defined throughout the specification and claims.

In the drawings forming part of this specification:

Figure 1 illustrates a calendar as it would appear when hung upon the wall with the free ends of the calendar sheets curved outwardly to indicate the several sheets which normally hang flat and straight, one upon the other.

Figure 2 illustrates a front view of the binder hanger sheet showing the hanger tongue projecting upward from the top of the binder display sheet.

Figure 3 is a rear view of the binder hanger sheet showing the tongue within the body of the sheet and to indicate the portion of the body which is stamped out to form the hanger tongue.

Figure 4 illustrates one of the loose-leaf sheets 10 of the calendar as it would appear when died out from a single piece and indicating the sheet in flat formation with the dotted lines indicating the lines on which the sheet is folder to form a pocket on the lower end of the sheet.

Figure 5 is an enlarged sectional detail of a portion of the calendar on the line 5—5 of Figure 1.

In the drawings the calendar A is formed by a series of loose-leaf sheets 10 which appear in their died out formation in Figure 4.

Each sheet 10 is formed with an elongated, horizontal slot or opening 11, which permits the sheets to be supported by suitable hanger means which will be hereinafter fully set forth. The sheets 10 may be formed with a pocket 12 by folding the lower portion 13 on the horizontal front line 14 and then securing the flaps 15 at either side of the portion 13 by folding the sheet on the vertical fold lines 16. The flaps 15 are pasted or glued to the back of the sheet 10 when the portion 13 is folded up in position to form the pocket 12. In this manner I provide a pocket loose-leaf calendar wherein the pockets 12 form means for receiving memorandum sheets or other articles which it is desirable to keep with the calendar A ordinarily for future reference.

The pockets 12 serve the purpose of providing a receptacle with each calendar month so that bills and other memorandums may be placed in the pocket and which ordinarily refer to the month showing on the front of the pocket.

A loose-leaf calendar of the character set forth is desirable for use in the home or in any other place where it is desirable to save the monthly calendar sheets for future reference. It is not necessary that each sheet 10 carry a pocket 12 on the lower free end of the same.

This form of calendar has been extensively used with a different form of binder hanger of

a more expensive type wherein metal parts are used to make the binder so as to effectively hold the sheets in a loose-leaf form. Here I have purposely designed the binder hanger sheet 17 in a manner so that it can be used as a display sheet covering the top of the sheets 10 and on which a picture 18 may be attached to provide a display to add beauty and character to the calendar A.

The binder hanger sheet 17 may be formed of any suitable material and preferably is made from heavier stock than the sheets 10 to provide a stiff or firm cover sheet 17 for the tops of the sheets 10, as illustrated in Figure 1, and from which the hanger tongue 19 may be cut.

In forming the binder hanger from the sheet 17, before cutting the tongue 19 from the body of the sheet 17, it is desirable to reinforce that portion of the front of the sheet 17 by a sheet of cloth 20, which will strengthen the sheet 17 and also strengthen the hanger tongue 19. The tongue 19 is formed with vertical slots or openings 21 to permit a pencil or writing instrument 22 to be inserted through the slots 21, as illustrated in Figure 1 if it is desired.

The binder hanger sheet 17 may be reinforced along its top edge by a metal member 23, which is ordinarily called tinning the edge of the same, and which acts to reinforce the upper edge of the sheet 17 and to hold the same straight. The function of the binder hanger sheet 17 with the tongue 19 is to hold the loose-leaf sheets 10 collectively together, and this is accomplished by threading the tongue 19 through the slots 11 in the sheets 10, as illustrated in Figure 5. Figure 5 is a section of an upper detail of the calendar A and shows only a few sheets supported by the hanger tongue 19, with the tongue 19 engaged by the nail 24 projecting from the wall 25 to show the manner in which the calendar A is supported when in use. Thus, in operation the binder hanger sheet supports the loose-leaf sheets 10 freely removable by detaching the tongue 19 from the nail 24 and releasing the sheets 10 from the tongue 19. This permits the sheets 10 to be changed at any time so that a new sheet may be brought to forward position on the calendar. This permits the months of the year to be disclosed on the bottom of the sheets 10, and when one month is past, this sheet is ordinarily moved to the rear of the series of sheets and the current month is exposed on the bottom of the sheets 10.

Where the pocket 12 is formed on the bottom of the sheets 10, the calendar indicia may appear on the outside of the sheet or that portion of the pocket forming the front thereof.

It will be apparent that I have provided a very economical means of supporting loose-leaf sheets for a calendar or other display. The display sheet 17 provides the tongue 19, which is cut from the area of the sheet and bent in a manner to hang upright when the calendar is in displaying position. It will also be apparent that a calendar of this character can be readily packed or shipped flat with the tongue 19 turned down and lying within the opening 26, which is formed in the sheet 17 when the tongue 19 is died out of the body of the sheet 17. Thus the construction and formation of my calendar is desirable. I do not use any metal parts to make the same, and the costs are reasonable because the hanger binder sheet can be made of paper or reinforced paper, and yet I provide a good looking calendar or display which can be economically made and supplied at a reasonable price to the customer.

I claim:

1. A loose-leaf calendar including a series of sheets each having an elongated horizontal slot formed in the top thereof, a binder-hanger formed from a single sheet, a supporting hanger tongue stamped from within the edges of the body of said binder hanger sheet with one edge in connection therewith to form a tongue adapted to extend through said slots in said sheets and projecting upwardly from said binder hanger sheet to form a hanger for supporting said sheets in a loose-leaf manner.

2. A loose-leaf calendar and display comprising a series of sheets, a horizontal slot formed in each of said sheets near the top thereof, binder means for supporting said sheets collectively including a front display sheet and a supporting tongue cut from said sheet within the edges thereof adapted to extend through said slots in said sheets and drawn in an upward manner to form a hanger, the cut out portion of said display sheet being covered by a picture display which extends over the major portion of the front of said display sheet.

3. Loose-leaf display including a display cover sheet for the tops of the leaves of the display, a series of loose-leaves each having a slot formed therein and adapted to be supported under said display sheet and held collectively together thereby in a manner so that the sheets may be readily disengaged from said display sheet, a portion of said display sheet being cut away from within the edges of said display sheet to provide a hanger tongue which extends through the loose-leaf sheets and projects above the display sheet for supporting the loose-leaf display.

4. A loose-leaf display comprising a series of loose-leaves, each of said leaves having an elongated, horizontal slot, a leaf supporting display sheet adapted to cover the top portion of said loose-leaf sheets, a portion of said display sheet being cut from within the edges of the body thereof to form an extended supporting tongue for said loose-leaf sheets adapted to extend through said horizontal slots in said sheets and be formed in an upwardly extending manner to provide a hanger tongue, and reinforcing means secured to said display sheet.

5. In a loose-leaf calendar, a series of sheets each having a slot formed therein, a hanger front sheet, a tongue member cut from said hanger sheet from within the edges thereof and having one edge spaced from the upper edge of said sheet in connection with said sheet and parallel to the top edge of said sheet adapted to be positioned rearwardly of said front sheet through said slots of said series of sheets and folded upwardly to form a hanger and removably support said sheets.
